US00D884770S

(12) **United States Design Patent** (10) Patent No.: **US D884,770 S**
(45) Date of Patent: **** May 19, 2020**

(54) **GUN CAMERA**

- (71) Applicant: **ZHEJIANG DAHUA TECHNOLOGY CO., LTD.**, Hangzhou, Zhejiang (CN)
- (72) Inventors: **Guojian Xue**, Hangzhou (CN); **Li Chen**, Hangzhou (CN)
- (73) Assignee: **ZHEJIANG DAHUA TECHNOLOGY CO., LTD.**, Hangzhou (CN)
- (**) Term: **15 Years**
- (21) Appl. No.: **29/701,224**
- (22) Filed: **Aug. 9, 2019**

Related U.S. Application Data

- (62) Division of application No. 29/589,342, filed on Dec. 30, 2016, now Pat. No. Des. 857,078.

(57) **CLAIM**

The ornamental design for a gun camera, as shown and described.

DESCRIPTION

FIG. 1 is a perspective view of a first embodiment of a gun camera configured with an antenna showing our new design; FIG. 2 is a front view of the gun camera configured with the antenna;

FIG. 3 is a rear view of the gun camera configured with the antenna;

FIG. 4 is a right view of the gun camera configured with the antenna;

FIG. 5 is a left view of the gun camera configured with the antenna;

FIG. 6 is a top view of the gun camera configured with the antenna;

FIG. 7 is a bottom view of the gun camera configured with the antenna;

FIG. 8 is a perspective view of a second embodiment of a gun camera showing our new design;

FIG. 9 is a front view of the gun camera;

FIG. 10 is a rear view of the gun camera;

FIG. 11 is a right view of the gun camera;

FIG. 12 is a left view of the gun camera;

FIG. 13 is a top view of the gun camera; and,

FIG. 14 is a bottom view of the gun camera.

The broken lines depict portions of the gun camera in which the design is embodied that form no part of the claimed design.

1 Claim, 14 Drawing Sheets
